UNITED STATES PATENT OFFICE.

HERBERT E. FENNER, OF BRYN MAWR, PENNSYLVANIA.

AUTOMOBILE-LOCK.

1,395,337.

Specification of Letters Patent.

Patented Nov. 1, 1921.

Application filed July 8, 1920. Serial No. 394,784.

To all whom it may concern:

Be it known that I, HERBERT E. FENNER, a citizen of the United States, residing at Bryn Mawr, county of Montgomery, and 5 State of Pennsylvania, have invented a certain new and useful Improved Automobile-Lock, of which the following is a specification.

This invention has relation to a device for 10 preventing the unauthorized removal of a motor vehicle and has more particular relation to the providing of a key-operated switch which may be applied to the vehicle dash-board or some other suitable part 15 thereof, the switch being so arranged and connected with respect to the source of ignition and spark plugs that the vehicle motor will not properly fire unless the switch is operated by the particular key designed 20 therefor.

The leading object of the present invention may be said to reside in the providing of a simple, compact, efficient and comparatively inexpensive switch of this type which 25 may be readily applied to motor vehicles in a few moments' time. Other and further objects will hereinafter appear.

The invention consists of the improvements hereinafter described and finally 30 claimed.

The nature, characteristic features and scope of the invention will be more fully understood from the following description taken in connection with the accompanying 35 drawings forming part hereof, and in which:

Figure 1, is a view principally in horizontal section of a switch embodying features of the present invention applied to the dash-board of a motor vehicle.

40 Fig. 2, is a front elevational view of Fig. 1, and

Fig. 3, is a rear elevational view of Fig. 1.

For the purpose of illustrating my invention I have shown in the accompanying 45 drawings one form thereof which is at present preferred by me, since the same has been found in practice to give satisfactory and reliable results, although it is to be understood that the various instrumentalities of 50 which my invention consists can be variously arranged and organized and that my invention is not limited to the precise arrangement and organization of the instrumentalities as herein shown and described.

55 In the drawings 10 designates one of two

blocks both of which are of insulating material. In practice this block is of annular configuration. The inner face of this block is provided with an annular recess 11 for a purpose to presently appear. The inner 60 face of the block 10 is provided with a plurality of terminals 12. The number used depends upon the number of cylinders employed upon the motor vehicle to which the switch is attached. For illustrative purposes four are shown in the drawings. Leading from each terminal 12 to the outer face of the block 10 is a binding-post 13, the binding posts in practice being connected to a magneto or battery ignition. Seated 65 within the annular recess 11 of block 10 is the sleeve of the second terminal block which block is designated 14. The terminal block 14 is provided with an annular flange 70 by which the same may be secured for instance to the dash-board 16 of a motor vehicle. In the drawings I have shown a ring 75 17 fitted over said flange and secured to the dash-board by screws, although obviously other means of attachment may be employed. Terminals 19 are secured to the block 14, and binding posts 20 lead from said terminals through the walls of said sleeve and through apertures 21 in the terminal block 10. The binding posts 20 are 80 85 in practice connected to the cylinder spark plugs of a vehicle motor. Mounted between the two terminal blocks is a rotatable contact-block 22 in the form of a disk also of insulating material. The inner and outer 90 faces of this contact-block have fitted thereto, respectively, contacts 23 and 24. The set of contacts 23 are electrically inter-connected with the set of contacts 24 in an irregular manner as shown in Fig. 2 by wires 95 a—b—c—d so that the contact-block must be moved a predetermined distance in the proper direction in order to establish the correct electrical contact between terminals 12 and 19, otherwise the proper firing order 100 of the cylinders cannot be had. In order to secure the proper movement of contact block 22 I employ a lock of conventional form, as a "Yale-lock." The non-rotatable part 25 of the lock is fixed to the dash-board 16 and the rotatable barrel 26 is extended through the terminal block 14 and is fixed as at 27 to the contact-block 22. By the insertion of key 28 within the lock and moving the same in the proper direction for 105 110

the required distance the necessary electrical connections for proper firing are procured and vice-versa, movement in the opposite direction tends to break proper electrical connections and establish improper electrical connection thus upsetting proper firing order.

It will now be apparent that I have devised a novel and useful construction which 10 embodies the features of advantage enumerated as desirable in the statement of the invention and the above description and while I have in the present instance shown and described the preferred embodiment 15 thereof which has been found in practice to give satisfactory and reliable results, it is to be understood that the same is susceptible of modification in various particulars without departing from the spirit or scope of 20 the invention or sacrificing any of its advantages.

What I claim is:

1. In a device of the character stated superimposed fixed terminal blocks of insulating material each provided with contact pieces, a disk of insulating material rotatably mounted between said terminal blocks which disk is provided with spaced contact pieces electrically inter-connected in an irregular manner, a key barrel passing through one of said terminal blocks and fixed to said disk and a key adapted for coöperatively engaging said barrel to shift said disk for establishing registry of the 30 contact pieces of said disk with the terminal 35

blocks whereby correct timing order of motor cylinders may be effected.

2. In a device of the character stated a dished terminal block of insulating material, means for supporting said block in a fixed 40 manner, a disk of insulating material rotatably mounted within said terminal block, spaced contact pieces electrically inter-connected in an irregular manner carried by 45 said disk, other contact pieces at least some of which are carried by said block, a key barrel passing through said means and fixed to said disk and a key adapted for coöperatively engaging said barrel to shift said disk for establishing registry of the disk 50 contact pieces with the other of said contact pieces whereby correct timing order of motor cylinders may be effected.

3. In a device of the character stated a dished terminal block of insulating material, 55 means for supporting said block in fixed position, a disk of insulating material rotatably mounted within said block, spaced contact pieces electrically inter-connected in an irregular manner carried by said disk, other contact pieces at least some of which are carried by said block and means insertible through the block supporting member for shifting said disk to establish registry of the disk contact pieces with the other of said 60 contact pieces whereby correct timing order of motor cylinders may be effected.

In testimony whereof, I have hereunto signed my name.

HERBERT E. FENNER.
